Primary Examiner — Daniel D Bui(74) *Attorney, Agent, or Firm* — Muncy, Geissler, Olds & Lowe, PLLC(57) **CLAIM**

The ornamental design for a keyed communication jack, as shown and described.

DESCRIPTION

FIG. 1 is a perspective view of the keyed communication jack showing my new design;
FIG. 2 is a front view thereof;
FIG. 3 is a rear view thereof;
FIG. 4 is a left side view thereof;
FIG. 5 is a right side view thereof;
FIG. 6 is a top plan view thereof; and,
FIG. 7 is a bottom plan view thereof.

The even-broken line in the figure drawings is included to show unclaimed subject matter only and forms no part of the claimed design, the dash-dot line represents the boundaries of the claimed design.
